UNITED STATES PATENT OFFICE.

ARTHUR E. SCHULZ, OF CHICAGO, ILLINOIS.

APPARATUS FOR TURNING AND CLEANING BAGS.

Application filed August 31, 1921. Serial No. 497,288.

To all whom it may concern:

Be it known that I, ARTHUR E. SCHULZ, a citizen of the United States, residing at 218 N. Hamlin Ave., Chicago, in the county 5 of Cook and State of Illinois, have invented a new and useful Improvement in Apparatus for Turning and Cleaning Bags, of which the following is a specification.

My invention relates more particularly to 10 apparatus for turning and cleaning flexible bags such as those made of fabric, of the type employing a hollow open-ended member adapted for communication with a suitable source of suction and adapted to have 15 applied to the open end thereof, the mouth portion of the bag to be turned and cleaned.

My primary object is to provide improvements in apparatus of the general character 20 stated, to the end that the turning and cleaning operation will be performed in a highly satisfactory manner, and the apparatus be rendered capable of operating upon a maximum number of bags in a given length of 25 time. Certain of my objects specifically stated, are to provide an apparatus, the exertion of suction in the open-ended member of which shall be under the control of the operator, whereby in the application of the bags to said member the suction may be 30 caused to be non-acting on the bag until the bag is in the desired position relative to the member, so that the suction action will not act prematurely on the bag; and to provide 35 an apparatus which shall be simple of construction and positive in operation.

Referring to the accompanying drawings:

Fig. 1 is a view, somewhat diagrammatic in nature, of a bag turning and cleaning apparatus constructed in accordance with 0 my invention, the apparatus illustrated being shown as provided with a plurality of the open-ended members referred to. Fig. 2 is a view in vertical sectional elevation of one of the similar open-ended members referred to. Fig. 3 is an enlarged section taken at the line 3-3 on Fig. 2 and viewed in the direction of the arrows. Fig. 4 is a broken view in vertical elevation of a modification of the structure shown in the preceding figures; and Fig. 5 an enlarged section taken at the line 5-5 on Fig. 4 and viewed in the direction of the arrows.

In the particular illustrated embodiment of the invention, the open-ended members referred to and to which the bags to be

turned and cleaned are applied, are represented at 6, these members preferably extending in substantially vertical position with the open ends, represented at 7, opening downwardly. Two of the members 6 60 are shown, but it will be understood that the invention is also applicable to the employment of more or less of these members, the latter being shown as communicating at their open ends with pipes 8 which open 65 into a pipe 9 communicating with the suction inlet of any suitable suction-producing device represented at 10, the outlet of which communicates with a pipe 11, which would lead to any suitable point for discharge of the dust removed from the bags by the suction action. The suction device 10 is shown as provided with a pulley 12, which would be belted to any suitable power device (not shown) for driving the device 75 10.

The member 6 is shown as of general cylindrical form, its lower open end 7 being preferably contracted, as shown, relative to the body portion of the member 6. The 80 member 6 is preferably constructed of sheet metal and is provided at its upper end with a series of inwardly extending flanges 13, which are preferably each of the same length, and so positioned that the spaces between adjacent ones thereof are of substantially the same length as these flanges, as shown. Surrounding the upper end of the cylindrical member 6 is a ring 14 presenting at its upper edge a horizontally and outwardly extending annular flange 15, supported by means of bolts 16 extending therethrough and through the horizontally extending annular flange 17, provided on the lower edge of a ring 18 surrounding, and 95 rigidly secured to, the lower end of the pipe 8, the latter being preferably outwardly flaring in a downward direction as shown.

The upper end of the member 6 is provided with a round disc 19 containing a 100 series of segmental openings 20 radiating from the center thereof, this disc being of such diameter that it overlaps, throughout its periphery, a portion of the ring 14 which it superposes, this disc being preferably provided on its under surface with annular ribs 19a, which may be rings secured thereto and arranged to extend across the openings 20 for a purpose hereinafter described. The disc 19 is rigidly secured by rivets, as rep- 110

resented at 21, to the flanges 13, thereby rendering these two parts of unitary construction. Superposing the disc 19 is a disc 22 containing segmental radially disposed openings 23 preferably of the same shape and size as the openings 20 and spaced apart the same distance as the latter. The disc 22 extends at its annular margined edge between the rings 14 and 18, the bolts 16 passing therethrough and holding it against rotation. By preference the bolts 16 extend through spacers 24 located between the disc 22 and the flange 15 of the ring 14, these spacers being of such thickness that when the nuts of the bolts 16 are tightened to clamp together the rings 14 and 18, the disc 22 and the spacers 24, the disc 19 will not be clamped between the disc 22 and ring 14, but will be free to rotate, together with the body of the member 6, upon the ring 14, while maintaining a substantially air-tight joint between these parts.

From the foregoing it will be understood that when the body portion of the member 6 is rotated to one position, the openings 20 in the disc 19 will be in registration with the openings 23 in the disc 22, and suction will be exerted in the member 6, and when moved to a position in which the openings 20 are out of registration with the openings 23, suction in this member will be arrested.

In the use of the apparatus, the operator grasping the bag to be turned and cleaned at opposite sides of the mouth portion thereof by his two hands, and assuming the valve device described for the member 6 to be closed, positions the mouth of the bag against the lower open end 7 of the member 6 and at the same time grasps this member 40 and rotates it sufficiently to rotate the disc 19 to a position in which this valve device will be open, the suction action thus produced in the member 6 drawing the bag into the latter, while the bag is held by the operator at its mouth against the open end of the member 6, and thereby turning the bag inside out and withdrawing the dust therefrom, which is sucked by the device 10 through the pipes 8 and 9 and discharged 50 through the pipe 11. After the bag has been subjected to suction action sufficiently long to effect the removal of the dust therefrom, the operator still grasping the mouth portion of the bag and the open end of the member 6 rotates the latter, and with it the disc 19, to a position in which the valve device, of which this disc is a part, is in closed position, whereupon the suction ceases and the bag is then removed.

60 The valve device referred to, in addition to controlling the exertion of suction in the member 6, also serves as a means for preventing the sucking of the bag into the pipes 8 or 9, should the operator release his grasp 65 upon the mouth portion of the bag during

its subjection to the suction action, the rings 19^a insuring against the drawing of the bag, especially when of light material, into the openings in the discs.

The modification shown in Figs. 4 and 5 70 illustrate another embodiment of valve means for controlling the exertion of suction in the member 6. In this arrangement, instead of providing the valve device as explained of the construction in the preceding 75 figures, the pipe 8 is provided with a valve represented generally at 25 and adapted to be operated by the foot of the operator. The valve shown comprises two segmental discs 26 secured to shafts 27 which extend crosswise of the pipe 8 and are journaled therein adapting the discs 26 to extend in alignment crosswise of the pipe 8 and close the latter, or extend in depending position as represented by dotted lines in Figs. 4 and 5 to 80 open the pipe 8 to the exertion of suction therethrough, depending on the position occupied by these shafts. Adjacent ends of the shafts 27 are provided with pinions 28 which mesh with each other, one of these 90 shafts being provided with a crank 29 connected at its outer end with a pitman 30, the lower end of which is connected with a treadle 31 pivotally supported at 32, the valve device referred to being moved out of 95 closed position by depressing the treadle 31 against the action of a spring 30^a, which latter operates, when the operator removes his foot from the treadle, to restore the valve to closed position.

100 It may be stated that as to the feature of providing a valve control for the suction, this is of considerable advantage in a construction of this character, as the operator is permitted to position the bag on the member 6 while this member is closed to suction, the operator thereupon opening the valve to permit the suction to turn and clean the bag. This feature of the invention not only insures the proper turning and cleaning of 110 the bag, but also conserves suction with the manifest advantage.

115 While I have illustrated and described certain particular constructions embodying my invention, I do not wish to be understood as intended to limit it thereto, as the same may be variously modified and altered without departing from the spirit of my invention.

120 What I claim as new and desire to protect by Letters Patent is:

1. Bag cleaning apparatus comprising, in combination, a movably supported open-ended tubular member adapted for the application to its open end, of the mouth portion of a bag to be cleaned, a source of suction in communication with said member, and valve means adapted to be actuated by the movement of said member for controlling suction exerted in the latter.

2. Bag cleaning apparatus comprising, in combination, a rotatably supported open-ended tubular member adapted for the application to its open end of the mouth portion of a bag to be cleaned, a source of suction in communication with said member, and valve means adapted to be actuated by rotating said member.
3. Bag cleaning apparatus comprising, in combination, a rotatably supported open-ended tubular member adapted for the application to its open end, of the mouth portion of a bag to be cleaned, a source of suction in communication with said member, and valve means formed of relatively movable members, one of which is an apertured disc movable with said tubular member and serving when in one position to open said member to said source of suction and when shifted to another position to close said member to said source of suction.
4. Bag cleaning apparatus comprising, in combination, a conduit through which suction is exerted, said conduit containing an apertured member forming one part of a valve device, an annular member supported from the lower end of said conduit and spaced therefrom, and an open-ended tubular member provided with an outwardly extending flange at which said member extends into said space referred to for rotatably supporting said member on said conduit, the upper portion of said tubular member having an aperture cooperating with said disc, for the purpose set forth.

ARTHUR E. SCHULZ.
